UNITED STATES PATENT OFFICE.

EMIL T. DREIER, OF HANAPEPE, HAWAII.

WATER-FILTER.

SPECIFICATION forming part of Letters Patent No. 637,095, dated November 14, 1899.

Application filed May 31, 1899. Serial No. 718,828. (No model.)

To all whom it may concern:

Be it known that I, EMIL T. DREIER, of Hanapepe, Kauai, Hawaii, have invented a new and Improved Water-Filter, of which the following is a full, clear, and exact description.

My invention relates to an improvement in water-filters designed particularly for household use, although capable of other use; and it consists of the novel features which will be hereinafter described and claimed.

Reference is to be had to the accompanying drawings, forming a part of this specification, in which similar characters of reference indicate corresponding parts in both figures.

Figure 1 is a longitudinal section through my device, and Fig. 2 is a cross-section upon the line 2 2 of Fig. 1.

Within an outer casing A, which consists of a short metal cylinder, is placed a cylinder G, which is provided with a longitudinal bore, which, however, stops short of the upper end of said cylinder. This cylinder at its lower end or base screws into a circular flange C², which projects from the lower head C of the cylinder or casing A. This lower head is secured to the casing A by having a threaded flange C' screwing upon the lower end of the casing, and the upper end of the casing is closed by a screw-head B, which is secured to the casing in a similar manner.

At the center of the upper head is a projecting boss b, which has a hole passing through the same and threaded to receive the water-supply pipe I, provided with a valve J, by means of which the flow of water through the filter may be regulated.

The cylinder G, besides having the longitudinal bore mentioned, has a number of small bores or passages g, extending from said central bore to the exterior of the cylinder. These are filled with a fibrous filtering material, as sponge, which permits the water to reach the central carbon stick H more readily than would be possible through the body of the cylinder G, and yet filters and delays the water somewhat. Within the central bore is placed a stick H of carbon or similar filtering material. The cylinder G is sufficiently smaller than the casing A to leave a water-passage about the cylinder.

The head C is provided with a central boss C³, which has a central passage communicat-

ing with the end of the carbon stick H and threaded exteriorly to receive the threaded collar d of the chamber D. This chamber D is herein shown as being of spherical shape and is filled with sand K. Within its lower end is screwed a plug E, which is provided with a central bore or passage, through which the water escapes from the filter. This plug extends some distance within the sand-receiving chamber D and has the inner extension E' thereof provided with perforations, forming, in effect, a sieve to permit the escape of the water while retaining the sand. This plug is also provided with a valve F, by means of which the flow of water may be controlled.

The operation of the device is as follows: The upper end of the casing A is connected with any suitable source for water, as a faucet I. Water is admitted between the casing A and the cylinder G and obtains access to the central filtering-stick H through the holes g, which are filled with a fibrous material, as sponge. Water after filtering through the carbon stick H enters the sand-chamber K, where it is further filtered, being discharged through the valve E.

Having thus fully described my invention, I claim as new and desire to secure by Letters Patent—

1. A filter, comprising a casing having a water-supply connection thereto, a cylinder extending within said casing and having a longitudinal bore therein, and exteriorly connecting passages extending outwardly from said bore, and a carbon filtering-stick in said bore, the casing having a discharge-passage communicating with one end of the carbon stick, substantially as described.

2. A filter, comprising a casing having a water-supply connection therewith, a removable cap having a discharge connection therewith, a cylinder adapted to be secured to the said cap within the casing and having a central bore, and openings communicating from said bore to the exterior of the cylinder, said cylinder being smaller than the casing to provide a water-space between them, a carbon stick filling the bore of the cylinder, and a water-discharge communicating with said bore, substantially as described.

3. A filter, comprising a casing having a water-supply connection therewith, a removable

cap having a discharge connection, a cylinder adapted to be secured to said cap within the casing and having a central bore, and openings communicating from said central bore to the exterior of the cylinder, said cylinder being smaller than the casing to provide an annular water-space between them, a carbon stick filling the bore of the cylinder, a sand-

filled chamber communicating with said bore, and a screen-protected discharge therefor, substantially as described.

EMIL T. DREIER.
